ROTARY DRILLING RIG

Walter T. Caldwell and John P. Lang, Enid, Okla., assignors to The George E. Falling Supply Company, Enid, Okla., a corporation of Oklahoma

Application April 6, 1938, Serial No. 200,390

6 Claims. (Cl. 255—22)

This invention relates to rotary drilling rigs and particularly to those equipped with power augmenting apparatus for controlling or applying pressure on a drill bit.

5   Rotary drilling apparatus of this character usually employ a hollow drive rod that is slidably keyed to a rotary driving member and provided with a chuck for clutchingly engaging the drill pipe that extends therethrough. The power 10 augmenting apparatus is connected with the drill rod so as to exert a control pressure upon the drill bit through the drive rod, chuck, and the drill pipe engaged thereby. The effective movement of the power augmenting device is 15 relatively short so that it is necessary to release the chuck and readjust it relatively to the drill pipe many times during drilling operations, particularly when drilling relatively soft formations where the progress of the bit is rapid. This 20 slows down the drilling time and results in high cost of operation.

It is, therefore, the principal object of the present invention to provide a rotary drilling apparatus of this character that is equipped with 25 a power augmenting device whereby hydraulic pressure and rotary power are applied directly to a conventional type kelly rod connected into the drilling string so that the hydraulic power may be selectively released to permit the kelly rod to 30 be rotated and moved independently of the power device.

In accomplishing this and other objects of the invention, as hereinafter pointed out, we have provided improved details of structure, the preferred form of which is illustrated in the accompanying drawings, wherein:

Fig. 1 is an elevational view of a drilling rig embodying the features of the present invention.

Fig. 2 is a vertical section through the power 40 augmenting device and the driving mechanism for respectively driving and controlling pressure on the drill bit.

Fig. 3 is a detail horizontal section on the line 3—3 of Fig. 2 illustrating the chuck for connecting the power augmenting device with a kelly rod.

Fig. 4 is a section through the head of one of the power augmenting cylinders on the line 3—3 of Fig. 2.

50   Fig. 5 is a section through one of the cylinders on the line 5—5 of Fig. 2.

Referring more in detail to the drawings:

1 designates a drilling rig including a mast 2 that is supported upon a platform 3 carried upon 55 the chassis of a motor vehicle 4. The rear end

of the platform 3 is provided with a recess 5 within which is slidably mounted a rotary drilling unit 6 constructed in accordance with the present invention.

The unit 6 includes a base frame 7, having foot 8 flanges 8 for engaging the platform to suspend a pair of cylinders 9 and 10 upon the respective sides of a driving mechanism 11, later described.

The flange 7 includes a cross head 12 having a central gear housing 13 and laterally extending 10 arms 14 and 15 that are provided with vertical 15 openings 16 through which the cylinders 9 and 10 extend. The cylinders 9 and 10 comprise 20 tubular bodies having threaded ends 17 and 18 25 for mounting cap-like cylinder heads 19 and 20 respectively. The upper heads 19 engage against 30 spacing collars 21 and 22 that are also threaded on the upper ends of the cylinders and engage 35 against the upper faces of the arms to cooperate 40 with sleeves 23 in clamping the cylinders to the 45 base frame, the sleeves 23 engaging against the lower faces of the arms 15 and against the lower 50 heads 20 of the cylinders, as clearly shown in Fig. 2.

To reduce the over-all height of the unit, the 25 cylinders are preferably mounted so that they 30 depend through the recess in the platform but 35 terminate a sufficient distance above the ground 40 to not interfere with movement of the base frame 45 out of drilling position when it becomes necessary 50 to run casing or perform other operations 55 incidental to drilling of earth formations.

Slidable within the cylinders are pistons 24 and 25 to which are connected rods 26 and 27 having their upper ends projecting through 35 packing glands 28 and 29 provided in the upper 40 cylinder heads. The outer ends of the rods 45 have reduced shanks extending through openings 30 and 31 in the arms 32 and 33 of a movable 50 cross head 34. The threaded shanks project 55 through the arms and are provided with nuts 35 and 36 for drawing the arms against the shoulders 37 and 38 formed by the reduced 60 extensions.

Extending laterally from the arms are integral 45 sleeve-like bosses 39 and 40 supporting guide rods 41 and 42 slidable through openings 43 in a 50 flange 44, projecting from the base frame 7, as 55 best shown in Fig. 4.

The gear housing 13 has upper and lower walls 50 45 and 46 provided with registering openings 47 and 48 to mount antifriction bearings 49 and 50 respectively, the outer races 51 and 52 of the 55 bearings being retained in fixed position within the openings by closure plates 53 and 54 secured 55

by fastening devices, such as cap-screws 55 and 56 respectively. The inner races 57 and 58 of the bearings are retained against shouldered seats 59 and 60 that are provided within a driving sleeve 61 having reduced extensions 62 and 63 projecting through openings 64 and 65 of the closure plates 53 and 54, the joints therebetween being sealed by packing rings 66 and 67 to retain a lubricant within the gear housing.

10 Mounted on the upper end of the driving sleeve is a wear ring 68 carrying a compressible packing 69 that is retained in compression against the kelly rod 70 later described, the packing being engaged in a recess 71 of a retaining plate 72. 15 The retaining plate has an annular flange 73 provided with a depending annular portion 74 engaging over an annular shoulder 75 of the upper cover plate to center the retaining plate. The retaining plate is anchored in position by 20 fingers 76 projecting inwardly from lugs 77 that are secured by the fastening devices 55.

Secured to the driving sleeve by means of a spline 78 is a driving gear 79 having teeth 80 engaging with a driving pinion 81 that is rotatably mounted within the gearing housing and fixed to a drive shaft 82 connected with a suitable prime mover carried upon the vehicle. The driving sleeve, including the retaining plate, is provided with an axial opening 83 corresponding to the cross-section of a kelly rod 70 that is extended therethrough so that when the driving sleeve is rotated the kelly rod is rotated thereby and is floatingly slidably therethrough progressive with downward movement of the drill bit, the 35 drill bit being connected with the drill pipe attached to the lower end of the kelly rod, as in conventional practice.

Formed in the movable cross head 34, in axial alignment with the driving sleeve, is an opening 40 85 for mounting the outer races 86 and 87 of antifriction bearings 88 and 89. The bearings 88 and 89 are preferably of roller type and arranged to take thrusts acting in either direction relatively to the longitudinal axes thereof under 45 movement of the pistons 24 and 25, as later described, the bearings being retained in position by annular rings 90 and 91 that are secured to the upper and lower sides of the cross head by screws 92 and 93.

50 The inner races 94 and 95 of the bearings carry a sleeve 96 provided with an axial opening 97 having sliding fit with the kelly rod so that the kelly rod projects therethrough and is drivingly connected with the sleeve. The lower end of the 55 sleeve has a laterally extending flange 98 supporting a spacer ring 99 that engages against the inner race of the lower bearing and which cooperates with a similar spacing sleeve 100 and a collar 101 to spacingly retain the bearings relatively to the sleeve. The upper end of the sleeve projects above the cross head and is externally threaded to mount the collar 101 of a chuck 102 whereby the cross head is selectively anchored to the kelly rod. The collar 101 rotates within 60 the upper bearing retaining ring and is packed relatively thereto by a packing ring 103 to cooperate with a similar ring 104 mounted within the lower plate to retain a lubricant for the bearings.

70 The chuck 102 is best shown in Fig. 3 and has a plurality of radially extending bores 105 terminating in rectangular recesses to slidably mount clutch jaws 106 having transverse teeth 107 to engage the side faces of the kelly rod by means of adjusting screws 108 threadedly engaged with-

5 in bushings 109 that are threaded into the outer ends of the bores. The inner ends of the screws have heads 110 engaging within flanged recesses of the jaws so that the screws are swivelly mounted therein but are adapted to move the 10 jaws to and from the kelly rod when the heads 110 thereon are rotated by a suitable wrench (not shown). The chuck body also includes a cap plate 111 for retaining the jaws, the cap plate being secured to the body by cap screws 112, as shown in Figs. 2 and 3.

The upper end of the kelly rod is provided with the usual swivel head 113, carrying a bail 114 connected with a tackle mechanism 115 employed in handling the drilling string. Connected with the swivel head is the usual hose 116 through which a drilling fluid is circulated to the drilling string through the swivel head and through an axial channel 117 of the kelly rod. The pistons are moved in the cylinder to raise and lower the 20 cross head 34 by a fluid pressure medium admitted to the respective ends of the cylinders through ports 118 and 119, the ports being connected by conduits 120 connected with a control valve 121, whereby pressure medium may be selectively admitted to the upper or lower portions of the cylinders, depending upon the desired direction of movement for the cross head 34.

In using the apparatus, the kelly rod slides freely through the sleeves so that it may be raised or lowered by means of the tackle mechanism. The kelly rod is rotated through the driving sleeve upon rotation of the ring gear 49 to effect rotation of the drill bit that is connected with the lower end of the drilling string. When the drill bit is operating satisfactorily through relatively soft formations, the jaws are slackened off from engagement with the kelly rod and the kelly rod moves freely therethrough and through the driving sleeve progressively with the downward 40 progress of the bit. The kelly rod is, therefore, independent of the power augmenting mechanism. Upon encountering a hard formation where it is desirable to apply pressure on the bit in excess of the weight of the drilling string, the 45 jaws are engaged with the kelly rod to grip the cross head thereto. Pressure fluid is then admitted through the upper ports of the cylinders to force the pistons downwardly and exert a downward pressure on the drilling string. 50

As the depth of the hole increases, the weight of the drilling string may be such as to produce an excessive pressure on the drill bit. When this occurs the pressure may be relieved by engaging the jaws with the kelly rod, and admitting the 55 pressure fluid to the lower ends of the hydraulic cylinders so that a lifting force is applied on the pistons to sustain the weight of the drilling string.

It is apparent that in the structure illustrated, the rotative power is applied directly to the 60 kelly rod independently of the power augmenting mechanism; however, when it becomes necessary to use the power device, the jaws are engaged directly with the kelly rod so as to exert a pressure control on the kelly rod as desired. 65

What we claim and desire to secure by Letters Patent is:

1. In a rotary drilling rig, a power augmenting unit including a pair of cylinders, a piston in each cylinder, a rod connected with each piston, 70 a cross head connecting the piston rods, means spacingly connecting the cylinders and forming an enclosing housing, a kelly rod driving sleeve having a bore directly engaging a kelly rod, means rotatably mounting the kelly rod driving 75

sleeve in the housing, a chuck sleeve having a bore passing the kelly rod, a chuck on the chuck sleeve and arranged to grip the kelly rod at points thereon in accordance with the length of the piston stroke relatively to the length of the kelly rod to effect movement of the kelly rod through said driving sleeve, means rotatably mounting the chuck sleeve in the cross head whereby said chuck sleeve rotates with the kelly rod, and driving means in the housing having driving connection with the kelly rod driving sleeve.

4. In a drilling apparatus, power augmenting means, a cross head actuated by said power augmenting means having an axial bore, a sleeve in said bore for passing a kelly rod therethrough, reversely arranged thrust bearings including outer races at the respective ends of the bore and inner races on said sleeve, closure plates covering the ends of said bore to retain the outer races, stop means on said sleeve engaging one of the inner races, and a chuck on the end of the sleeve opposite said stop means and engaging the other inner race to cooperate with said stop means in retaining said sleeve in fixed rotative relation with said cross head.

5. In a drilling apparatus, power augmenting means, a cross head actuated by said power augmenting means having an axial bore, a sleeve in said bore for passing a kelly rod therethrough, reversely arranged thrust bearings including outer races at the respective ends of the bore and inner races on said sleeve, closure plates covering the ends of said bore to retain the outer races, a stop means on said sleeve engaging one of the inner races, spacing means on the sleeve spacing said inner races, and a chuck threaded on the end of the sleeve opposite said stop means to draw said inner races in rigid assembly with said sleeve.

6. In a rotary drilling rig, a power augmenting unit including a pair of cylinders, pistons in the cylinders, a rod connected with each piston, a cross head connecting the rods, means spacely connecting the cylinders and forming an enclosed housing having registering openings in the upper and lower sides thereof, bearings supported in axial alignment with said openings, a kelly rod driving sleeve rotatably supported in said bearings and having a bore to directly engage a kelly rod that is extended therethrough, a chuck sleeve separate from said driving sleeve, thrust bearings rotatably supporting the chuck sleeve in the cross head, a chuck carried by said last named sleeve having jaws arranged to grip-
